S. T. Arnold

By

Obed B. Billman Attorney

UNITED STATES PATENT OFFICE.

SATTERLEE T. ARNOLD, OF PADUCAH, KENTUCKY, ASSIGNOR TO SOUTHERN TEXTILE MACHINERY COMPANY, OF PADUCAH, KENTUCKY, A CORPORATION OF KENTUCKY.

ELECTRIC SADIRON.

Application filed April 25, 1921. Serial No. 464,266.

To all whom it may concern:

Be it known that I, SATTERLEE T. ARNOLD, a citizen of the United States, residing at Paducah, in the county of McCracken and 5 State of Kentucky, have invented certain new and useful Improvements in Electric Sadirons, of which the following is a specification.

My invention relates to improvements in 10 electric sad irons and more particularly to an improved thermostatic switch or control device adapted to prevent the over heating of the iron and particularly to prevent the burning out of the resistance element or 15 heating coil.

The primary object of the invention is to provide a generally improved device of the class indicated, which will be exceedingly simple in construction, cheap of manufacture, and efficient in use.

A further and very important object is to provide a thermostatic device of the class indicated in which the liability to damage or deterioration while in use is reduced to a 25 minimum.

A still further object is the provision of means for adjusting the parts whereby to regulate the temperature of the resistance coil or element and whereby the make and 30 break action of the contact elements may be regulated to conform to any desired or predetermined temperature of the iron and electric resistance or heater unit.

With the above mentioned and other ends 35 in view, the invention consists in the novel construction, arrangement, and combination of parts, hereinafter described, illustrated in one of its embodiments in the accompanying drawings, and particularly pointed 40 out in the appended claims.

Referring to the drawings, forming a part of this specification, Figure 1, is a side elevation, partly in vertical longitudinal section, of an electric iron constructed in accordance 45 with this invention.

Fig. 2, a top plan view of the base portion of the iron with the handle and surrounding casing removed, and illustrating in particular the thermostatic control device.

Similar numerals of reference designate 50 like parts throughout all the figures of the drawings.

The base or main body portion 1, of the iron may be of any suitable or convenient 55 construction, and so likewise as to the de-

tachable casing or cover 2, and the handle 3. The body 1, of the iron is provided within a suitable and convenient receptacle for the electric resistance element or coil of any suitable and convenient form, and these 60 parts forming no part of the present invention the same need not be described in detail.

Referring now to the improved thermostatic control device to which this invention 65 particularly relates, it will be seen that the electric control device or circuit breaker comprises, in the present instance, a substantially U-shaped member extending longitudinally of the main body portion of the 70 iron and insulated therefrom by means of a strip of insulating material 1^a, as shown most clearly in Fig. 1, of the drawings. The circuit breaker comprises relatively fixed and movable arms 4, and 4^a, respectively, 75 connected at their base portions by means of a transverse portion 4^b, the relatively fixed side arm 4, being secured or anchored to the upper portion of the main body 1, of the iron by means of attaching or securing 80 screws 5.

As a means of actuating the relatively movable or floating arm 4^a, in accordance with variations in the temperature of the subjacent iron body and particularly the 85 resistance or heater coil (not shown) a block 6, is interposed between the base or connected portions of the arms 4, and 4^a, said block being formed of suitable material such as aluminum, or the like, adapted to expand 90 and contract with the variations in temperature of the forward portion of the heating coil, and it will be obvious that by reason of the location of the thermostatic block 6, the expansive and contractive movements of 95 the latter will be greatly extended or amplified in the free end of the floating arm 4^a, and the contact element carried thereby.

As a means of providing suitable contact elements in the inlet and outlet conductors 7, and 7^a, respectively, leading to the resistance element or unit in the iron, the relatively fixed or anchored side arm 4, is provided with an insulated opening 4^c, through which the wire 7, is extended, said wire being connected to a contact element 7^b, in the specific form of a flexible metallic conducting strip insulated from the inner side of the arm 4, by means of an insulation strip 7^c. The free end of the contact element 7^b, is adapted to 10 11

be controlled or regulated by means of an adjusting screw 8, threaded in a threaded opening in the fixed arm 4, said screw 8 leading to one side of the iron casing 2, for adjusting the circuit breaker or contact element in accordance with the different desired heats or temperatures.

As a means of providing a cooperating contact element 9, on the movable or floating arm 4^a, the latter is provided with a strip of conducting material on its outer side insulated therefrom by means of a suitable strip of insulating material 9^a, said contact, in the present instance, being in the specific form of a longitudinally extending member on the outer side of the arm and a transversely extending bridge member extending toward the free end of the contact element 7^a, and adapted to make contact with the latter as shown most clearly in Fig. 2, of the drawings.

The base of the contact strip 9, on the outer side of the floating arm 4^a, is connected to a second section of the inlet conductor wire 7, through a suitable connecting element 9^b, so that when the contact elements are closed, thereby closing the circuit, the current will flow through the inlet conductor wire 7, and downwardly into the terminal portion 10, of the resistance element (see Fig. 2) and after passing therethrough passes out through the opposite terminal portion 10^a, and outwardly through the wire 7^a, connected to the contact element 11^a, of the socket 11.

It will be seen that the aluminum block 6, between the base portions of the arms 4, and 4^a, will expand and contract more readily than such arms, and it will be apparent that by adjusting the screw 8, in the relatively fixed arm 4, of the controller, the amount of heat necessary to open the circuit may be governed and the temperature of the electric iron may therefore be set within certain limitations.

The block 6, may be secured in position by means of an insulated attaching element 12, and the controlled members 4, 4^a, and 4^b, are preferably formed integral and of suitable metallic material adapted to yield and yet return to a normal position when the current is cut out or reduced.

From the foregoing description, taken in connection with the accompanying drawings, the operation and advantages of my invention will be readily understood.

Having thus described one of the embodiments of my invention, without having attempted to set forth all the forms in which it may be made, or all the modes of its use, what I claim and desire to secure by Letters Patent, is,—

1. In an electric iron, a U-shaped circuit breaker embodying relatively fixed and movable side arms carrying contact ele-

ments, and a thermostatic block interposed between said arms and adapted to control said movable arm and contact elements.

2. In an electric iron provided with a resistance unit, a U-shaped controller embodying a relatively fixed arm provided with a contact element and a relatively movable arm provided with a cooperative contact element, and a thermostatic block between said arms of said U-shaped controller in cooperative relation to said resistance unit and said movable arm.

3. In an electric iron, a body provided with a resistance unit, a U-shaped controller above the latter embodying a relatively fixed arm provided with a movable contact element and a relatively movable arm provided with a cooperative contact element, means on said fixed arm for adjusting said movable contact element, and a thermostat in cooperative relation to said resistance unit and said movable arm.

4. In an electric iron, the combination with an electric circuit including a resistance heater element; of a U-shaped controller device mounted above and insulated from said heating element, one of said arms being fixed and the other movable, a thermostat mounted within the base portions of said arms and adapted to actuate said movable arm, contact elements carried by said arms and normally in circuit with said electric circuit, and means for adjusting said contact elements to regulate the temperature of said resistance element.

5. In an electric iron, the combination with an electric circuit including a resistance element and an electric iron body heated thereby; of a U-shaped circuit breaker extending across said iron body above said resistance unit, one of said arms being relatively fixed and provided with an adjustable contact element in said circuit and the other arm being relatively movable and provided with a second cooperating contact element, and an expansible and contractable block interposed between the base portions of said arms.

6. In an electric iron, the combination with an electric circuit including a resistance element and an electric iron body heated thereby; of a U-shaped circuit breaker extending across and insulated from said iron body above said resistance unit, one of said arms being relatively fixed and provided with an adjustable contact element in said circuit and the other arm being relatively movable and provided with a second cooperative contact element and an expansible and contractable block interposed between the base portions of said arms and arranged above the front portion of said iron body and resistance element.

7. In an electric sad iron, the combination with an electric circuit including a

resistance element; of a circuit make and break device including relatively fixed and movable arms above said resistance element, said arms carrying contact elements, means adapted to move and control the latter and the other of said contact elements in accordance with the temperature of said resistance element.

5 carried by one of said arms for adjusting one of said contact elements, and a thermostatic element in cooperative relation to said resistance element and movable arm

In testimony whereof I hereby affix my signature.

SATTERLEE T. ARNOLD.
